United States Patent Office.

FRANCIS H. WALKER, OF BOSTON, MASSACHUSETTS.

Letters Patent No. 97,996, dated December 14, 1869.

IMPROVEMENT IN BUTTON-HOLE CUTTER.

The Schedule referred to in these Letters Patent and making part of the same.

To all whom it may concern:

Be it known that I, FRANCIS H. WALKER, of Boston, in the county of Suffolk, and State of Massachusetts, have invented a new and improved Button-Hole Cutter; and I do hereby declare that the following is a full, clear, and exact description thereof, reference being had to the accompanying drawings, making part of this specification, in which—

Figure 1 is a perspective view of the improved instrument.

Figure 2 is a side view of the instrument, with a portion broken away to expose the compound levers.

Figure 3 is a top view of the instrument, with portions of its handles broken off.

Similar letters of reference indicate corresponding parts in the several figures.

The object of this invention is to improve button-hole cutters, by pivoting the jaw, to which the cutter is applied, to the stock of the instrument, and connecting this jaw, by means of a loose joint, to a handle, which is also pivoted to the stock of the instrument, thereby obtaining a compound leverage for working the cutter, and allowing this cutter to be either opened or closed without the use of a spring; also allowing the cutter to be kept closed when the instrument is not in use, as will be hereinafter explained.

To enable others skilled in the art to understand my invention, I will explain its construction and operation.

In the accompanying drawings—

A, A' represent the handles of the improved button-hole cutter, which are constructed with eyes upon their ends like a pair of shears.

B is the stock of the instrument, which is constructed upon the handle A', and grooved longitudinally to receive the pivoted end of handle A and the pivoted end of the cutter-jaw C.

B' is the jaw of the handle A', which is a flat plate, constructed on one end of the stock B, and adapted for receiving upon it the adjustable cutter-bed D, as shown in figs. 1 and 2.

The handle A', the stock B, and the jaw B', are made in one piece, as shown.

The lever-handle A is pivoted at g in the groove h, formed in the stock B, and the end of the shortest arm of this lever-handle has a concave depression or

socket, i, made in it for receiving a corresponding convex surface, n, which is formed on the shortest arm of a lever-jaw, C, which jaw is pivoted, at e, in the groove h, formed in stock B, as shown in figs. 1, 2, and 3.

The pivoted jaw C has a cutter, a, secured to it, adapted for cutting button-holes in cloth, which cutter is so applied to its jaw as to cut upon the adjustable bed D, when the handle A is moved toward the handle A'.

The cutter-bed D is pivoted, at b, to the jaw B', and secured rigidly to this jaw in any desired position, by means of a screw, e', the shank of which passes up through a segmental slot made through the jaw B', and is tapped into the cutter-bed.

This bed B is reversible, and adapted for button-holes of different lengths.

It will be seen, from the above description, that the cutter-jaw C is not a part of the handle A, but that it is pivoted to the stock B of the instrument, independently of the handle A, which moves this jaw.

I obtain, in this way, a compound leverage, which will greatly lessen the power required to force the cutting-edge of the cutter a through thick or thin material.

I also connect together the short arms of the jaw-lever C, a handle-lever, A, by means of a loose joint, which will allow the jaw-lever to be operated without the employment of a spring, for it will be seen that the lever-handle A will act upon the jaw C, either to open or to close it.

One great advantage attending my improvement is, that when the instrument is not in immediate use, the cutter a may be closed upon the bed D, and will remain in this position, where it will not be liable to injure anything, nor become injured itself.

Having described my invention, What I claim as new, and desire to secure by Letters Patent, is—

The combination of adjustable cutter-bed D, with a cutter-carrying jaw, C, which is connected to a lever-handle, A, by a loose joint, substantially as and for the purpose described.

FRANCIS H. WALKER.
